(57) **CLAIM**

The ornamental design for a sauté tongs, as shown and described.

DESCRIPTION

FIG. 1 is a top, front, right side perspective view of sauté tongs showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof;

FIG. 7 is a rear elevation view thereof; and,

FIG. 8 is a top front perspective view thereof, shown in a closed position.

1 Claim, 6 Drawing Sheets
